UNITED STATES PATENT OFFICE.

JAMES A. JOYCE, OF CLEVELAND, OHIO.

ELECTRIC-RAILROAD SWITCH.

SPECIFICATION forming part of Letters Patent No. 709,156, dated September 16, 1902.

Application filed December 17, 1901. Serial No. 86,237. (No model.)

To all whom it may concern:

Be it known that I, JAMES A. JOYCE, of Cleveland, in the county of Cuyahoga and State of Ohio, have invented a new and Improved Electric-Railroad Switch, of which the following is a full, clear, and exact description.

The object of my invention is to provide a new and improved electric-railroad switch which is especially adapted to the use of electric railroads and so arranged that it may be operated from the car as desired by the motorman.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 shows a top view of the switch. Fig. 2 shows a sectional view on line A A with parts shown in full. Fig. 3 is a sectional view on line C C, showing parts in full. Fig. 4 is a sectional view on line B B, showing parts in full. Fig. 5 shows the track and the switch in position with the wiring, &c. Fig. 6 shows the tracks and switch in position with a different method of wiring, &c.

The electric-railroad switch illustrated in Fig. 1 is provided with a rock-shaft R, upon the upper side of which is a tapering part, commonly called a "switch-point," which acts to deflect the wheels from one track to another. The tapering part or switch-point is made so that one side is parallel to the straight track and the other side is parallel to the switch-track or made to be concentric to a circular track. The frame F, supporting the rock-shaft, with its tapering part or switch-point, is arranged to have at one end a water-tight compartment into which is placed the electromagnetic operating device. The frame F, supporting the rock-shaft and switch-point, is arranged so that the switch-point is made to operate in a longitudinal slot in the upper part of the frame adapted to the said switch-point and having a recess R' on either side of the track-grooves to receive the small end of the said switch-point to prevent the wheels from

striking the point and also to cause them to go on the straight or curved track easier and smoother. The part of the frame F supporting the rock-shaft has a hole H in the lower part for drainage. The switch-point has lugs projecting from either side, which prevent the wheels of wagons from going into the opening and also large pieces of refuse which may be brought to it by the water running down the track. The top part of the frame F is provided with grooves, which form the continuation of the track. This part of the frame may be made of hard steel, which will stand the wear better than the rails and need not be replaced when new rails are required. The supporting-frame F may be made in any convenient form and have water-tight joints where they may be required. The top part should preferably have a joint in line D D, which will make it easily accessible from the top and will not require the street to be torn up in case any repairs are necessary. The frame is provided with lugs on either end for supporting the rails. The frame is provided with a packing-gland around the rock-shaft to make the compartment water-tight and at the same time allow the shaft to move in its bearings and at the same time be water-tight. The frame F is provided with a U-shaped support S for supporting the electromagnetic field-coil C. This support is arranged to support the arc-shaped field-coil C and to allow it to be removed by lifting it out of the U-shaped support S. To the end of the rock-shaft are fastened the armature-coils C' C² C³ C⁴ and having pole-pieces extended and provided with rings encircling the arc-shaped field-coils, thus forming a means of electromagnetically moving the rock-shaft by having the electric current enter the armature-coils C' and from C' go to C² and from C² go to the arc-shaped field-coil C and from C to the rails and return to the power-house. By the electric current going in this way the armature is made to move in one direction, and by having the electric current enter the armature-coil C³ and pass from C³ to C⁴ and from C⁴ to the arc-shaped field-coil C and from C to the rails and return to the power-house the reverse movement is obtained. The above method of operating is obtained by having sections of the track, as at T' and T², Fig. 5, insulated, so that

the current cannot return to the ground or to the adjacent rails. To the insulated sections of rail T^1 is fastened a wire, which enters the coils C^3 , Fig. 3, as described above, will cause the switch to open for the curve, so the car passes over the insulated sections of rail, and when it reaches the insulated sections of rail T^2 the current enters the coil C' , Fig. 3, as described above, and will cause the switch to be closed, thus keeping the switch closed to all cars except those that are to go around the curve. When it is desired to run cars on the straight track, the current is shut off on the car until it passes over the insulated sections of rail. Thus the switch is under the control of the motorman handling the car. The car can easily get momentum enough to carry it over the insulated sections of rail.

There are several different methods of operating this switch and of wiring the same. I will describe another method, and that is to have two sections of the track insulated, as at T^3 and T^4 , Fig. 6, and having a wire from T^3 enter the coil C^3 and pass as above described will cause the switch to open, and having a wire from T^4 enter the coil C' and pass as above described will cause the switch to close, and in this case the switch is under the control of the motorman to open it or close it, just as he desires, by simply turning the current on or off by his controller. In either case the car can easily get momentum enough to carry it over either of the short insulated sections of rail. I have not described the minor details of wiring and insulating, &c.; but it is assumed that this is to be done in the ordinary practical manner, such as any first-class electrician would wire and insulate the whole work.

40 The same purpose may be accomplished by insulating one section of rail in each track against the return-current, and in this way the same result will be accomplished with a little less work, as a sufficient amount of the current will pass through the switch-circuit to operate the switch with one rail in the track insulated.

I do not wish to confine myself to the one method, as it is plainly evident that either method may be used to accomplish the same purpose.

The switch may be operated by insulating one or more sections of the trolley-wire, so that the current must pass through the switch in passing to the car in a manner similar to the method used for the insulated sections of rail.

It may be necessary to have an electric heater in the water-tight compartment in cold climates, and in such cases the water-tight compartment will extend farther under the rock-shaft to keep the same from freezing in extreme cold weather.

65 The switch may be operated without the use of electricity, and in that case the water-tight compartment will be omitted and the switch turned by hand, using a rod to move

it from one side to the other. It may be necessary in some cases to move the electric switch by hand when the current is off and 70 horse-cars are temporarily used. In such a case the armature is so nearly balanced that it may be easily moved by hand, using a rod to move it from side to side.

Having thus described my invention, I 75 claim as new and desire to secure by Letters Patent—

1. In a switch with a movable shaft having a switch-point on the upper side, an armature fastened to the shaft having extended pole-pieces encircling the field-coil and acting in conjunction with the same to electromagnetically move the shaft and switch-point, a frame with grooves in the upper side, a drainage-hole under the shaft and switch-point, a water-tight compartment having a U-shaped support for field-coils and adapted to support the shaft and cover the electric mechanism, and an insulated section of trolley-wire from which the current passes to the armature and field-coils, when a car passes over the said insulated section of trolley-wire to open or close the switch, substantially as shown and described.

2. In a switch with a movable shaft having a switch-point on the upper side, an armature fastened to the said shaft, acting in conjunction with a field-coil to electromagnetically move the same and a frame adapted to support and to cover the shaft and the electrical 100 mechanism, substantially as shown and described.

3. In a switch with a movable shaft having a switch-point on the upper side, an armature fastened to the shaft, having extended pole-pieces encircling the field-coil and acting in conjunction with the same to electromagnetically move the said shaft and switch-point, and a frame with grooves in the upper side, a longitudinal slot in which the switch-point works, a drainage-hole under said shaft, and a water-tight compartment to support and cover the shaft and the electric mechanism, substantially as shown and described.

4. In a switch with a movable shaft having a switch-point on the upper side, an armature fastened to the shaft having extended pole-pieces encircling the field-coil and acting in conjunction with the same to electromagnetically move the shaft and switch-point, a frame with grooves in the upper side, a longitudinal slot in which the switch-point works, a drainage-hole under the said shaft and switch-point, a water-tight compartment to support the shaft and cover the electric mechanism and an insulated rail from which the current passes to the armature and field when a car passes over the said insulated rail which will cause the switch to open or close as desired, substantially as shown and described.

5. In a switch with a movable shaft having a switch-point on the upper side, an armature fastened to the shaft having extended pole-pieces encircling the field-coil and acting in

conjunction with the same to electromagnetically move the shaft and switch-point, a frame with grooves in the upper side, a longitudinal slot in which the switch-point works, a drainage-hole under the shaft and switch-point, a water-tight compartment having a U-shaped support for field-coils and adapted to support the shaft and cover the electric mechanism, and insulated rails from which the current

passes to the armature and field-coil, when a car passes over the said insulated rails to open or close the switch, substantially as shown and described.
